CLAIM

The ornamental design for a casing for foldable tool set, as shown and described.

DESCRIPTION

FIG. 1 is a perspective view of a casing for foldable tool set showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof illustrating usage thereof.

The broken lines in FIGS. 1-8 are for illustrative purposes only and form no part of the claimed design.
